US00D779524S

(12) **United States Design Patent** (10) Patent No.: US D779,524 S
Hotchkiss et al. (45) Date of Patent: ** Feb. 21, 2017

- (54) **DISPLAY SCREEN OR PORTION THEREOF WITH A GRAPHICAL USER INTERFACE FOR ANALYTICS**

(71) Applicant: **Domo, Inc.**, American Fork, UT (US)

(72) Inventors: **Wes Hotchkiss**, Salt Lake City, UT (US); **Sam Thomas**, Lehi, UT (US)

(73) Assignee: **Domo, Inc.**, American Fork

(**) Term: **14 Years**

(21) Appl. No.: **29/523,051**

(22) Filed: **Apr. 6, 2015**

(51) **LOC (10) Cl.** **14-04**

(52) **U.S. Cl.**
USPC **D14/486**

(58) **Field of Classification Search**
USPC D14/485-495
CPC G06F 17/212; G06F 17/3005; G06F 17/30112; G06F 17/30716

CLAIM

The ornamental design for a display screen or portion thereof with a graphical user interface for analytics, as shown and described.

DESCRIPTION

The FIGURE is a front view of a display screen or portion thereof with a graphical user interface for analytics showing the new design with environment in broken lines. Within the drawing, the broken lines show the display screen or portion thereof and the portions of the graphical user interface which are excluded from the claim and form no part of the claimed design.
